UNITED STATES PATENT OFFICE.

WILLIAM E. CHOATE, OF WESTERLY, RHODE ISLAND, ASSIGNOR, BY MESNE ASSIGNMENTS, TO FEDERAL FINANCE CORPORATION, A CORPORATION OF MASSACHUSETTS.

MARKING MACHINE.

Original application filed August 15, 1916, Serial No. 115,112. Divided and this application filed April 22, 1931. Serial No. 464,558.

To all whom it may concern:

Be it known that I, WILLIAM E. CHOATE, a citizen of the United States, residing at Westerly, in the county of Washington and State of Rhode Island, have invented certain new and useful Improvements in Marking Machines, of which the following is a full, clear, and exact description.

This invention relates to marking machines of the kind adapted to make impressions from heated typed members or dies. The present application is a division of my application Serial No. 115,112, filed August 15, 1916, and is directed to those aspects of the invention originally disclosed in that application having more particularly to do with the heating of the dies and the control of the heating.

My invention will best be understood by reference to the following description of the illustrative machine shown by way of example in the accompanying drawings, wherein:

Fig. 1 is a side elevation of the machine partly broken away;

Fig. 2 is a central vertical section on an enlarged scale through the tool carrier, the tool actuating mechanism and a portion of the work support;

Fig. 3 is a horizontal section taken on the line 3—3 of Fig. 2;

Fig. 4 is a view on an enlarged scale of the thermostat shown in Fig. 3;

Fig. 5 is a view of the heater unit shown partly in side elevation and partly in vertical section;

Fig. 6 is a bottom view of the heater unit shown in Fig. 5;

Fig. 7 is a horizontal section on an enlarged scale showing the temperature controlling devices; and

Fig. 8 is a wiring diagram.

The machine here shown is of the general type shown in my Patent 1,128,225 and has a base 9 from which rises a hollow standard 11 having a horizontal track or guideway 13 on which moves the head 15 which is provided with the depending neck 17 on which is rotatably mounted the die carrier 19. An operating lever 21 may be actuated to depress the plunger 23 which in turn acts on the plunger dies 25 mounted in carrier 19

forcing them out into contact with the work on a suitable work support as 27. The return movement of the lever 21 is adapted to cause the head 15 to travel on the track 13, thus to provide spaces between successive letters. It will be understood that rotative movement of the carrier 19 is adapted to bring a selected die 25 under the plunger 23. The general construction of the machine may be similar to that shown in my prior patent above referred to, and does not need more extended description here.

Referring to Fig. 2, I will now more particularly describe the construction of the carrier 19 and the means whereby the plunger dies 25 carried thereby may be heated. As shown in that figure the carrier 19 comprises an annular casting provided with a hub portion 29 revolving on the bearing formed by the depending neck 17, and a depending cylindrical flange 31 in which are housed the dies 25, the plungers on which the dies are formed being provided with suitable springs 33 which normally withdraw them to the position shown in Fig. 2 with the ends of the dies housed within the flange and from which they are thrust out by the action of the plunger 23. The dies are held in position preferably in the manner more fully described in the application of which this is a division by means of a top ring 35 cooperating with tabs 37 secured to the plungers.

The depending flange 31 provides an annular chamber adapted to receive an electric heating unit from which heat may be conducted through the comparatively thin wall of the flange 31 to the die receiving chambers therein. In the illustrative embodiment of the invention the heating unit is adapted to rotate with the carrier and I have herein shown an angular member 39 adapted to fit in the cavity of the carrier with the angle facing that formed by the depending flange 31 and adapted to sustain a resistance coil 41 closely adjacent the inner surface of the flange 31. The member 39, shown in detail in Fig. 5, is preferably of pressed asbestos and may be formed with the staggered lugs 43 about which the coil 41 may be looped in an undulatory path as shown, thus providing for a comparatively great length

of coil and consequent efficient heating of the dies. As shown in Fig. 2 the member 39 carrying the coil may be secured in position in the hollow of the carrier by a cover plate 45 secured to the bottom of flange 31.

In the example of the invention here shown the electric current is brought to the coil 41 through the hollow neck 17. As herein shown, (Figs. 1 and 2) the conductors 47 and 49 leading up through the hollow standard 11 pass through the porcelain cap 51 which may be secured to and supported by internal ribs 53 on the neck (which ribs also may serve for purposes of heat radiation) and are connected respectively to terminals 54 and 55 in an insulating plate 57. This plate 57 is centrally secured to a plate 59 which forms a closure for the bottom of the neck and has a projecting portion holding the hub 29 on the neck and providing a bearing on which the former rotates. Herein the contact 55 is centrally disposed and the contact 54 is annular and suitable brushes 63 and 65, as best shown in Fig. 6, connected by the binding screws 67 to the terminals of the resistance coil 41, are adapted to cooperate with the terminals respectively.

The annular form of the heat insulating member 39 conserves the heat for application to the flange 31 and to the dies housed therein and also prevents the heat from being conducted to the rotative bearing of the die carrier. To further conserve the heat and to shield the operator of the machine therefrom the top plate or ring 35 may be hollowed as shown (Fig. 2) to receive a packing 69 of asbestos held in position by the plate 71. This packing may be suitably recessed to receive the metallic thermostat 73 (Figs. 3 and 4) having one end secured to the ring 35 and connected at its other end to an index 75 which may be pivoted on the cover plate 71, thus providing the operator with a visual indication of the temperature of the marking tools.

Current may be supplied to the heater from any suitable source through a connection plug 77 arranged at the base of the machine and, as shown in Fig. 1, the hollow base provides a convenient receptacle to house a frame in which is mounted controlling mechanism for the electric current such as will presently be described. In the present instance the electric mechanisms are received between two plates 79 and 81 of pressed asbestos held in spaced relation by the pillars 83 and provided with the insulating asbestos wall 85 between them. Referring to the wiring diagram, Fig. 8, current may pass from the positive pole through the signal lamp 87 which is, as shown in Fig. 2, presented in sight at the base of the machine, through conductor 47 to heating coil 41 and thence by conductor

49 to a binding post 91 to be referred to and by wire 93 to a series of resistance coils 95 constituting a rheostat for controlling the current, the resistance coils being provided with suitable contacts 97 with which the switch arm 99 carried by shaft 101 may make contact. The current passing through certain resistance coils of the rheostat, depending on the adjustment of the arm 99, then leads through arm 99 to shaft 101 and returns by wire 103 to the negative side of the line.

Especially since a machine of this type may be used only intermittently it is sometimes desirable to provide temporarily the full heating effect of the current quickly to prepare it for use and for this purpose means may be provided for short circuiting the resistance coils of the rheostat and herein a suitable switch 105, conveniently of the type presently to be described, may be provided having a bridge 107 for connecting a contact 109 on which is mounted post 91 with a contact 111 so that the current instead of passing through the resistance coils 95 passes from post 91 to contact 111 through wire 113 to shaft 101 and thence through wire 103 to the negative side of the line.

In Fig. 7 is shown more in detail the construction of the switch controlling the rheostat. As there illustrated, the shaft 101 is journalled in the insulating partition 85 and is acted upon by a spring 115 serving to press the switch arm 99 against the contacts 97. The shaft may be provided with a fin 117 adapted to enter a slot in a block of insulating material 119 carried on the end of a knob 121 journalled in the front wall 122 of the base of the machine and projecting at the front thereof as shown in Fig. 2 and providing a means for operating the rheostat. The knob may be provided with an index arm 123 having a projection 125 adapted to slip over a series of holes 127 in a dial plate 129 which provides for positioning the rheostat switch and giving an indication of its position.

The switch 105 is provided with suitable means for holding it normally open so that the full heat of the current is supplied to the resistance coil 41 only when it is so desired. A suitable mechanism for effecting this is shown in detail Fig. 7 wherein the contact 109 is adapted to be connected with the terminal 111 (not shown in Fig. 7 but see Fig. 8) by a suitable jump switch or bridge contact 107, slidably mounted on a pin 131 which has reverse conical portions 133 and 135 embraced by a circular coil spring 137 carried by said switch. A coil spring 141 tends to thrust said pin downward viewing Fig. 8. In moving to this position the circular spring contracts. The force of contraction is perpendicular to the axis of the

cone and has a component perpendicular to its surface and one parallel thereto. The action of this latter component causes the bridge 107 to move along the conical portion 135 away from and breaks the circuit at said fixed contacts 109 and 111. When said conical portion 135 is thrust upward against the resistance of the coil spring 141 the circular spring 137 rides along said conical portion 10 to the other conical portion 133 thereof and shifts the bridge into engagement with said contacts 109 and 111 thereby closing the circuit. When the two contacts are connected all of the resistance coils 95 will be cut out 15 of the circuit and the highest temperature for the heater will be obtained. To shift said bridge to close the circuit its pin 131 (Fig. 7) may project through the front wall of the frame into a cup casing 143. A hand 20 lever 145 has one end pivotally connected to said casing and its opposite free end projecting out through an opening 147 in said casing. This lever is normally held in its position shown in Fig. 7 by a coil spring 149 25 confined between the base of said casing and said lever. When it is desired to obtain the highest temperature for the heater the hand lever is thrust inward thereby causing the bridge 107 to connect the contacts 109 and 30 111 as described. As soon as the handle is released, however, the switch-actuating spring 141 will promptly break the circuit. This is important because it prevents any 35 possibility of inadvertently leaving the switch shifted to complete the circuit for raising the heater to its highest temperature.

In some cases it may be desirable to automatically maintain said highest temperature for the heater a predetermined length of 40 time without the inconvenience of manually holding the lever 145 in position to complete the circuit. To accomplish this the cup casing 143 may be provided with a spider 151 therein having a boss 153 projecting therefrom and receiving a pin 155 having one end 45 adapted to engage the lever in alignment with the switch pin, and its opposite end connected to a cap 157 having a flange 159 fitting on said casing. A coiled clock spring 50 161 may have one end anchored to a post 163 secured to said spider, and its opposite end connected to an internal boss 165 on said cap and tapped to the spider boss 153 referred to. A helical spring 167 may be mounted in 55 said bosses, encircle the pin 155 and be confined between the bases of said bosses. The cap flange may have projections 169 thereon to facilitate manual grasping and rotation thereof. Inward movement of the cap may 60 be limited by a stop 171 on the outer wall of said casing.

When it is desired to maintain the plug switch closed for a predetermined length of time the cap is rotated, thereby screwing the 65 same inward until the flange engages said

stop. This rotation of the cap will tension the springs 167 and 161 and thrust the pin 155 inward. The latter in turn will press on the lever 145 and thrust the switch actuating pin 131 inward, thereby completing the 70 circuit to the heater for producing the highest temperature. When the cap is released the springs energized as described will become effective to gradually rotate said cap in the opposite direction, thereby gradually 75 thrusting the pin 155 outward. This pin is followed by the lever 145 and the switch pin 131. When said pins, however, move outward sufficiently the switch will break the connection between contacts 109 and 111 and 80 the circuit to the heater will be broken. The pin 155 may have a flanged head to engage said spider and limit the outward movement of said pin.

When the cap is screwed inward to its 85 stop, the clock spring will be tensioned to its fullest extent and consequently immediately on release of the cap it will tend to rotate outward more rapidly than after the spring has relaxed somewhat. However, when the 90 cap is in its inward position, more of the threads on the parts 153 and 165 are engaged and the spring 167 is under compression and therefore firmly presses such threads together. The friction during the initial 95 movement of the cap is therefore greater and such movement is retarded. Thus the cap is automatically shifted gradually outward to allow the desired predetermined amount of time to elapse before the jump 100 switch 107 will snap to its position shown in Fig. 7 and break the circuit to the heater.

Referring to Fig. 7 it will be noted that the parts 117 and 119 may be separated by a simple movement in a vertical direction 105 viewing that figure and that the pin 131 simply projects through the front wall 122 of the machine base and may be withdrawn therefrom by a simple movement upwardly viewing Fig. 7. Referring, therefore, to 110 Fig. 1, it will be seen that when the lamp 87 is unscrewed all the heater controlling mechanism housed between the plates 79 and 81 may be withdrawn as a unit from the chamber formed by the hollow base of the 115 machine separating readily from the knob 121 and the controlling mechanism for the delayed action switch shown in Fig. 7. All this mechanism is thus conveniently removed for assembly and repair and is inserted in 120 the machine in a very simple manner.

Having described in detail the particular embodiment of my invention shown by way of example in the accompanying drawings, what I claim as new and desire to secure by 125 Letters Patent I shall express in the following claims.

Claims—

1. A marking machine comprising an annular carrier having a cylindrical flange, 130

- plunger dies normally housed in said flange, an angular annulus of heat insulating material opposing the angle of the carrier formed by the flange and a resistance coil received between them.
2. A marking machine comprising an annular carrier having a cylindrical flange, plunger dies normally housed in said flange, an angular annulus of heat insulating material opposing the angle of the carrier formed by the flange and a tortuous resistance coil carried by said annulus adjacent said flange.
3. A marking machine comprising an annular carrier having a cylindrical flange, plunger dies normally housed in said flange, an angular annulus of heat insulating material opposing the angle of the carrier formed by the flange and having staggered lugs and a resistance coil looped around said lugs.
4. A marking machine comprising a hollow support, an annular carrier rotatable thereon and having a cylindrical flange, plunger dies extending through said flange, an electric heating coil disposed adjacent said flange, conductors extending through the neck and brushes for the coil cooperating with said conductors.
5. A marking machine comprising a hollow support, an annular carrier rotatable thereon and having a cylindrical flange, plunger dies extending through said flange, an electric heating coil disposed adjacent said flange, conductors extending through the neck and having central and annular terminals and brushes for the coil cooperating with said terminals.
6. A marking machine comprising a hollow support, an annular carrier rotatable thereon, a plate secured at the end of the neck having a projecting portion to retain the carrier, tools in the carrier, a resistance coil for heating the same, conductors extending through the neck, terminals therefor in said plate and brushes connecting said coil to said terminals.
7. A marking machine comprising a support having a depending neck, a carrier rotatable thereon having a depending flange, plunger dies in said flange, a resistance coil disposed inwardly of said flange, a heat insulating partition inwardly of the coil and a heat insulating cover for the carrier.
8. A marking machine comprising a hollow support, an annular carrier rotatable thereon, tools about the circumference of the carrier, a resistance coil adjacent said tools and rotatable with the carrier, conductors leading through said neck and having brush connection with the coil.
9. A marking machine comprising an annular carrier member and an opposed angular heat insulating member, a heating coil between them and plunger dies carried in one flange of said carrier member.
10. A marking machine comprising a hollow support, an annular carrier rotatable thereon and having a cylindrical flange, plunger dies in the flange, an electrical heater housed by the flange and supply conductors therefor leading through the support.
11. A machine having an electrically energized element, a frame providing a chamber, a frame receivable in the chamber and in which are assembled controlling elements for the current, a wall of said chamber having one or more operating devices for said controlling elements, said devices adapted to interfit with the parts operated thereby on insertion of said frame in the chamber.
12. A machine having a frame including a chambered base and a hollow standard, an electrically energized element carried by the standard, conductors leading to the element through a hollow thereof, a frame receivable in the chambered base and in which are assembled controlling means for the current, a wall of said base having one or more operating devices for said controlling elements, said devices adapted to interfit with the parts operated thereby on insertion of said frame in the chamber.
13. A marking machine comprising an imprinting die, an electric coil for heating the same, a resistance in circuit with the coil and means for short-circuiting the resistance comprising a switch having means for normally holding the same open.
14. A marking machine comprising an imprinting die; an electric coil for heating the same, a resistance in circuit with the coil and means for short-circuiting the resistance comprising a switch having automatic means for opening the same after a determined time.
15. A marking machine comprising an imprinting die, an electric heater therefor, a rheostat in circuit with the heater, a line for short-circuiting the heater including a spring pressed bridge and a handle for holding said bridge in connecting position against its spring.
16. A marking machine comprising an imprinting die, an electric heater therefor, a rheostat in circuit with the heater, and a delayed action switch for temporary cutting out the rheostat.

WILLIAM E. CHOATE.
